(57) **CLAIM**

The ornamental design for a vacuum sealer, as shown and described.

DESCRIPTION

FIG. 1 is a top perspective view of an embodiment of a vacuum sealer;

FIG. 2 is a front side view of the vacuum sealer of FIG. 1; FIG. 3 is a back side view of the vacuum sealer of FIG. 1; FIG. 4 is a left side view of the vacuum sealer of FIG. 1; FIG. 5 is a right side view of the vacuum sealer of FIG. 1; FIG. 6 is a top side view of the vacuum sealer of FIG. 1; FIG. 7 is a bottom side view of the vacuum sealer of FIG. 1;

FIG. 8 is front side view of the vacuum sealer of FIG. 1, where the vacuum sealer is tilted backward such that a scale plate of the vacuum sealer is horizontal; and,

FIG. 9 is a back side view of the vacuum sealer of FIG. 1, where the vacuum sealer is tilted backward such that a scale plate of the vacuum sealer is horizontal.

1 Claim, 9 Drawing Sheets
